UNITED STATES PATENT OFFICE.

CHARLES CHILD AND ALEXANDER H. KEIR, OF WALLACE, CALIFORNIA.

SCRAPER.

1,117,324.

Specification of Letters Patent. Patented Nov. 17, 1914.

Application filed December 18, 1913. Serial No. 806,588.

To all whom it may concern:

Be it known that we, CHARLES CHILD and ALEXANDER H. KEIR, citizens of the United States, both residing at Wallace, 5 in the county of Calaveras and State of California, have invented certain new and useful Improvements in Scrapers; and we do declare the following to be a clear, full, and exact description of the same, such as will 10 enable others skilled in the art to which it appertains to make and use the same, reference being had to the accompanying drawings, and to the characters of reference marked thereon, which form a part of this 15 application.

This invention relates to improvements in scrapers, the object of the invention being to produce a scraper used for grading and leveling which can be wheel mounted and 20 controlled to perform its functions in an effective manner without over exertion on the part of the stock or the man operating the same.

A further object of the invention is to 25 produce a scraper which can be filled and emptied easily and rapidly or worked at different positions according as it is to be used for scraping or grading.

A still further object of the invention is 30 to produce a simple and inexpensive device and yet one which will be exceedingly effective for the purposes for which it is designed.

These objects, we accomplish by means of 35 such structure and relative arrangement of the parts as will fully appear by a perusal of the following specification and claims.

On the drawings, similar characters of reference indicate corresponding parts in 40 the several views.

Figure 1 is a top plan view of the complete scraper. Fig. 2 is a side elevation of the same. Fig. 3 is a sectional view taken on a line Y—Y of Fig. 1. Fig. 4 is a fragmentary view, partly in section, showing the connecting means of the scraper bowl with the balance of the structure. Fig. 5 is a sectional view of a spring controlled catch. Fig. 6 is a sectional view taken relatively on a line X—X of Fig. 5.

Referring now more particularly to the characters of reference on the drawings, the numeral 1 designates the scraper bowl which is flat on its bottom as at 2 and has its upper side and ends shaped in a curved manner into a substantial ellipse as at 3, the front

end of the bowl being provided with a cutting edge 4.

The numeral 5 designates a disk bolted to the member 1 on each end by bolts 6, each disk 5 having a series of projecting circular bearing members 7, 8 and 9 of varying dimensions. Turnably mounted on each of the members 7 is a drag bar 10 projecting to the front of the bowl 1 and having a cross brace bar 11 and connecting eyes 12 to which may be connected the draft means. Turnably mounted on the members 8 are the free ends of a frame 13 which projects to the rear of the bowl 1 and is provided with a cross bar 14 in which are journaled a pair of supporting swiveled wheels 15. A beam 16 is suitably connected to the members 13 and 14 and carries the driver's seat 17. Turnably mounted on each member 9 is a bracket 18 which projects to the immediate rear of the bowl 1 and where they are provided with bent ends 19 projecting between which is a handle member 20 riveted thereto by rivets 21, such rivets also securing to the members 19 and 20 a guide member 22 slidable in which is a latch 23 connected by a link 24 with an operating handle 25 on the outer end of the handle member 20. Said handle member 20 at its outer end is provided with a slidable loop 26 for the purpose of receiving a rope 27, if desired, for a purpose as will presently appear. The said link 24 projects into the slot 22^a of the slotted guide 20 where it is connected with the said latch 23, there being a spring 28 interposed between the latch 23 and the bottom of the slot 22^a to hold the said latch 23 in normal position. When in normal position, this latch 23 projects into a catch 29 on the rear of the bowl 1 to hold it in its fixed position as shown in Figs. 1 and 2. When said latch 23 is in the catch 29, this locks the bowl in rigid scraping position and then when it is filled with earth and it is desired to empty the same, the handle 25 is operated to pull the latch 23 out of the catch 29 and then since the bowl 1 is turnably mounted in the various members described and at a point near its front end, when it is released, the blade 4 engages the dirt and acts as the load to turn the bowl on its fulcrum point to inverted position to empty it and then when it has been emptied, it will turn on its curved portion 3 completely around and back into normal loading position when the latch 23 will again engage the catch 29 and hold it

If the entire load is not to be emptied in one spot but is to be spread along for grading purposes, the handle member 20 is lifted which will tilt the bowl to any degree desired for the purpose of spreading the dirt. Also for grading purposes, the rope 27 may be used to hold the handle member 20 at such position as will hold the bowl in a substantially perpendicular manner whereby the 10 blade 4 will grade and level the surface over which it is moved.

If it is desired to start the tilting operation of the bowl and handle without lifting it by the handle, we provide a pedal 30 on 15 a crank 31 journaled on the member 16 and provided on the other side with a projecting roller 32 adapted, when the pedal 30 is operated, to engage the handle member 20 and lift it until the bowl 1 is partly tilted 20 and then the blade 4 will act as the load to tilt the same to such point as is desired where it will be held by the rope 27.

From the foregoing description it will readily be seen that we have produced such 25 a device as substantially fulfills the objects of the invention as set forth herein.

While this specification sets forth in detail the present and preferred construction 30 of the device, still in practice, such deviations from such detail may be resorted to as do not form a departure from the spirit of the invention.

Having thus described our invention what 35 we claim as new and useful and desire to secure by Letters Patent is:—

1. A device of the character described comprising the combination with a wheel mounted frame, of a scraper bowl, a projecting bearing member on each side of said 40 bowl, said bearing members being turnably mounted in said frame, another frame turn-

ably mounted on said bearing members independently of said wheel mounted frame and of said scraper bowl, a handle member connected to said independent frame, a catch 45 carried by said handle member and removably engageable with said scraper bowl, as described.

2. A device of the character described comprising a scraper bowl, a member fixed 5 rigidly to each end of said scraper bowl and each having a plurality of projecting circular bearings, a drag frame freely mounted on one pair of said bearings, a wheel mounted frame freely mounted on another pair of 5 said bearings, a pair of brackets freely mounted on another pair of said bearings, a handle member on said brackets, a spring controlled latch on said handle member, and a catch on said bowl adapted to be engaged 6 by said latch, as described.

3. A device of the character described comprising the combination with a wheel mounted frame, of a scraper bowl, projecting bearing members on said scraper bowl, such bearing members being turnable in such frame, another frame turnably mounted on said bearing members and independently of said wheel mounted frame and said scraper bowl, a handle on said frame, a catch on 7 said handle removably engageable with said scraper bowl, and a pedal controlled lever on said wheel mounted frame engageable with said handle member to throw the same upwardly, as described.

In testimony whereof we affix our signatures in presence of two witnesses.

CHARLES CHILD.
ALEXANDER H. KEIR.
